ROAD GUARD

Eugene V. Camp, Atlanta, Ga.

Application January 14, 1933, Serial No. 651,798

28 Claims. (Cl. 256—13.1)

The invention relates to certain improvements in road guards of the type involving one or more continuous impact members supported under tension by spaced posts and has for its object to 5 provide a novel connection between the impact member and each post that will enable the proper degree of tension to be applied to and maintained in said impact member, said connection including a support, preferably a bowed leaf spring, secured to the post and a clamp engaging the impact member and the support. In the preferred form of the invention, the spring is provided with a reentrant bend in its face into which the impact member may be drawn by the clamp, whereby 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

under sufficient tensile stress to enable the same to carry out their normal and expected function in directing vehicular traffic impinging on the impact members, due to skidding or being forced off the road, back onto the road. Also when the impact member or members of the guard is in the form of one or more strips or bands of sheet metal, stretched along the supporting posts and maintained under tension, it is difficult to maintain an equal degree of tension on the upper and lower edges of the strip, when the road guard passes over the crest of a rise or dips into a hollow in the road. It is a primary purpose of this invention to provide a road guard in which the resilient impact member or members are continuous and may be maintained under uniform tension throughout the whole length of the guard, and, when the impact members are in the form of strips or bands of sheet metal and the like, uniform tension may be applied to the upper and lower edges of the strips or bands whenever any sudden change in the inclination of the road tends to produce a certain degree of slackness in the upper or the lower edge of the impact member.

While several different structural forms of the road guard have been illustrated in the accompanying drawings, it will be understood that each of them involves the same general operative principles and includes mechanical equivalent elements to effect the same specific results.

Referring to Figs. 1, 2 and 3 of the drawings, I indicates a post or support, preferably made of sheet metal and of generally triangular cross section, with one angular edge or face disposed normally or at right angles to the road or highway. A series of these posts are set up at proper intervals along the road or highway to be guarded and serve to support the impact members of the guard, which impact members serve to prevent vehicles accidentally leaving the road and, when the impact of the vehicle is at an angle to the surface of the impact member, the inherent resilience of the latter will deflect the vehicle back onto its normal course on the road. To effect this purpose without material injury to the guard or to the vehicle, it is necessary that the impact member or members possess inherent resilience and be maintained under tension throughout the length thereof.

As illustrated in the drawings, the portions of the road guard designed to receive the impact of vehicles tending to leave the road, are two parallel strips or bands 10, 10, which are preferably applied in continuous lengths from end to end of the guard and which are to be main- 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

tained under substantially uniform tension throughout their lengths. To effect this result in a highly efficient and economical manner, a special type of support is provided for connecting each strip to each post, each individual support being associated with a clamp by means of which the impact members are held securely in position and by means of which the desired degree of tension may be applied to the impact members and any degree of slackness in the impact members may be readily removed. As illustrated in Figs. 1, 2 and 3, the support is in the form of a two-ply leaf bowed spring, the ends of which are provided with perforations to receive screws 4, 4 by means of which the support is secured to the lateral faces of the post 1. The body portion of the bowed spring is generally annular or laterally curved from the end or leg portions 3, 3 and the outer face of the spring support is provided with a reentrant bend 5 affording laterally spaced portions cooperable with the impact member.

Instead of forming the support 2 of spring metal, the same may be made rigid, either in the form of a casting or a drop forging having the same general contour as the support 2. However, it is preferred that the support 2 be made of spring metal, so that said support will materially assist in taking up shocks and will materially relieve the stresses imposed on the impact members 10 by yielding laterally, or in a direction at right angles to the roadway. Furthermore, by making the supports 2 in the form of springs, a heavy impact delivered against any section of the road guard will be transmitted throughout the whole length of the guard and gradually dissipated, whereas, if the connectors 2 were rigid and inflexible, the force of impact of a vehicle striking a given section of the guard would be confined to that particular section which includes the impact members and two adjacent posts.

The purpose of the reentrant bend 5 in the front face of the support 2 is to provide a space into which the band 10 may be deflected and, to effect this deflection, there is associated with the support 2 an adjustable clamp adapted to draw the band 10 into the reentrant bend 5, to any desired degree. As shown in Figs. 1, 2 and 3, this clamp takes the form of a U-bolt 6 provided with nuts 7 on its threaded legs and a perforated strap 8 adapted to be engaged by the nuts. As clearly indicated in the drawings, the U-bolt straddles the band 10 and the spring support 2 at the intermediate portion of the reentrant bend 5 therein. From the foregoing description, it will be apparent that, when the continuous strips or bands 10 are secured to the supports 2 on the successive posts by the U-bolt clamps, any desired degree of tension may be applied to the strips by setting up the nuts 7 on the U-bolts and the strips will not only be stretched between the successive posts but will be locked firmly in position, so that, when the impact members are struck by a vehicle tending to leave the road, they will resist the movement of the vehicle and, by reason of their inherent resiliency and the tension under which they are maintained, will tend to force the vehicle back onto the roadway, and, if the impact of the vehicle is oblique to the direction of the roadway, the vehicle would be automatically deflected back into its normal direction of travel.

It will be apparent that any sudden change in the inclination of the roadway, as, for example,

when the same passes over the crest of a hill or dips into a hollow, either the upper or the lower edge of the strip or band 10 would take on a certain degree of slack, so that the uniform tensile stress on the band would be destroyed and the effectiveness of the guard decreased to a certain extent. This difficulty is overcome, however, by setting up one of the nuts 7 on the U-bolt 6 to a greater extent than the adjustment of the other nut on the same U-bolt, thereby causing the U-bolt to draw either the top or bottom edge of the strip 10 farther into the reentrant face of the support 2. For example, if the road guard passes over a sudden rise or the crest of a hill, the upper edges of the strips 10, 10 would be under tension, while the lower edges of the strips would be relatively slack. This slackness may be taken up and uniform tension applied to the strips by setting up the lower nuts 7 on each of the U-bolts. Similarly, if there is a sudden dip in the road, the lower edges of the strips 10, 10 would be under proper tension, but the upper edges of the strips would be slack and this slack may be taken up and uniform tension applied to the strips by setting up the top nuts 7 on each of the U-bolts.

The modification shown in Fig. 4 applies only to the particular type of post or support which, as indicated, is square in cross section. In this case, it is necessary only to spread the legs 3, 3 of each of the spring supports 2, or, in case the latter are formed as rigid members, to space the legs to engage the lateral faces of the posts, so that the legs may be securely locked to the posts by means of a through bolt 4.

In the modification shown in Figs. 5 and 6, the support or connector between the impact member and the post is in the form of a generally annular or elliptical leaf bowed spring 2', the ends of which adjacent the post are overlapped and perforated to receive a bolt 4', which passes through a hole in the post. The outer face of the bowed spring 2' is provided with the same type of reentrant bend 5' as in the preceding modification. The clamp employed in this type is identical with that shown in Figs. 1, 2 and 3 and operates in exactly the same manner. If desired, one corner of each end of the spring 2' may be bent at right angles to form a triangular tooth-like element 12, which may be driven into the face of the post to assist in holding the spring support 2' in proper alignment.

In the modification shown in Figs. 7 and 8, the supporting member is in the form of a relatively heavy spring 2'', which may be formed of a strip of spring steel of materially greater width than the spring as illustrated in the preceding modifications and is designed to support a relatively wide impact member 10''. The ends or legs of the spring member 2'' are adapted to be secured to the lateral faces of the post 1 by bolts 4 and the front face of the spring support 2'' is provided with a reentrant bend 5'', which is provided at its deepest portion with spaced perforations to receive bolts 17. The flexible strip or impact member 10'' is provided with corresponding holes adapted to register with those in the reentrant bend of the spring and to receive the bolts 17, which are mounted in a strap or batten 16 substantially semi-cylindrical in contour and is adapted to overlie the outer face of the impact member 10'' in the manner and form as clearly indicated in the drawings. Each of the bolts 17 is provided with a nut 18. The particular coordination of the strap 16, bolts 17 and nuts 18

constitute a clamp which is the full equivalent of the U-bolt and strap clamp employed in connection with the other forms of the invention, the only difference being that, in this case, the bolt members pass through the impact strip 10' and the spring member 2^a instead of embracing these elements, as is the case with the U-bolt clamp. In this modification, the necessary tension on the impact member 10' is applied by setting up the nuts 18. When the road guard is constructed on a level stretch of road, the nuts 18 are set up to the same extent, so that the portion of the strip 10' adjacent the strap 16 will be pulled evenly and uniformly into the reentrant bend in the face 15 of the spring 2^a and equal tension will be applied to the strip throughout. When the road guard passes over a sharp acclivity or through a declivity, equal tensions may be applied to the upper and lower edges of the strip 10 by setting up the 20 clamps differentially, as heretofore explained, that is to say, if the lower edge of the strip 10' is slack, it may be properly tensioned by setting up the nut on the lowermost bolt 17 to the necessary degree and then setting up the nut on the intermediate bolt to a lesser degree until the strip or band 10' is tensioned uniformly. Should the slack occur in the upper edge of the strip or band, the operation is reversed, that is to say, the nut on the upper bolt is set up to draw the 30 upper portion of the band deeper into the reentrant face of the spring, the bolt on the middle nut drawn up to a lesser degree but to a sufficient extent to render the band uniformly taut.

The modification shown in Fig. 9 applies only 35 to the particular form of the spring support, which, as shown, is in the form of a closed bowed leaf spring associated with a supporting post that is triangular in cross section. In this case, the bowed spring 2^b has a general configuration of a figure 8, the inner and outer faces being provided with reentrant angles 5^c and 5^b, the former hugging the lateral face of the post to which the spring is secured by a bolt 4^a. The reentrant bend in the front face of the spring serves the same purpose as that in each of the preceding 45 modifications and the type of clamp employed is identical with that shown in Figs. 7 and 8.

While the invention has been particularly described as involving a sheet metal strip as the impact member, it will be understood that it applies also to fabricated metallic bands or strips generally that are capable of being supported at one side of a series of posts.

What I claim is:

- 55 1. A road guard, comprising a series of spaced posts, a strip of sheet metal extending along the series of posts, and means for securing the strip to each post including a support secured to the post having a reentrant portion in the front face thereof, and an adjustable clamp engaging the strip and the support and adapted to draw the strip into the reentrant portion.
- 60 2. A road guard as described in claim 1, in which the support is a leaf spring bowed outwardly from its supporting post.
- 65 3. A road guard as described in claim 1, in which the clamp includes a U-bolt, a strap engaging the legs thereof and nuts on said legs, said U-bolt and strap embracing the impact member and the support at the reentrant portion in the latter.
- 70 4. A road guard as described in claim 1, in which the clamp includes a strap overlying the strip in alignment with the reentrant portion of the support, bolts passing through registering

openings in the strap, the strip and the support and nuts on said bolts.

5. A road guard as described in claim 1, in which the support is a bowed spring having its legs secured to the lateral faces of the posts and the reentrant portion of the support is disposed transversely of its arcuate face.

6. A road guard as described in claim 1, in which the support is an annular spring bolted to the front face of the post and the reentrant portion of the support extends transversely of the strip of sheet metal.

7. A road guard, comprising a series of spaced posts, a strip of metal extending along the series of posts, and means operatively interposed between at least one of the posts and the strip for adjusting the tension of one edge of the strip with respect to the other edge thereof, said means including a member having a reentrant face and an adjustable device cooperable with the strip adjacent said face.

8. In combination with a road guard including a series of spaced posts and a continuous strip of metal extending along one side of the series, of connectors for securing the strip to each post including means for taking up slack in either edge of said strip to substantially equalize the tension on both edges of the strip.

9. In combination with a road guard including a series of spaced posts and a continuous strip of metal extending along one side of the series, of resilient connectors for securing the strip to each post including means for taking up slack in either edge of said strip to substantially equalize the tension on both edges of the strip.

10. In combination with a road guard including a series of spaced posts and a continuous strip of sheet metal extending along one side of the series, of resilient connectors for securing the strip to the posts each connector comprising a bowed leaf spring having its free ends secured to the lateral faces of a post and its face attached to said strip.

11. A road guard comprising a series of spaced posts, a strip of metal extending along and supported by said posts, a member having a reentrant portion, and means connecting the strip to said member to permit one edge of the strip to be tensioned with respect to the other edge thereof.

12. A road guard comprising a series of spaced posts, a strip of metal extending along and supported by said posts, a member disposed on one side of said strip, and means cooperable with the opposite sides of the strip connecting the strip to said member to permit one edge of the strip to be tensioned with respect to the other edge thereof.

13. A road guard comprising a series of spaced posts, a flexible impact member carried by said posts, a member interposed between the impact member and at least one of said posts and having a reentrant front face, and means for drawing the impact member into said reentrant face.

14. A road guard comprising a series of spaced posts, a flexible impact member carried by said posts, a spring device having a reentrant front face interposed between said impact member and at least one of said posts, and means overlying the face of the impact member opposite said spring device for securing the impact member within said reentrant front face.

15. A road guard comprising a series of posts, a flexible impact member extending along said posts in spaced relation thereto, and a resilient connector secured to each post for connecting the impact member thereto, said connector comprising

- ing a bowed leaf spring having laterally spaced portions angularly disposed with respect to the impact member overlappingly cooperable with the associated post.
- 5 16. A road guard comprising a series of spaced posts, a flexible impact member extending along said posts in spaced relation thereto and resilient connectors for respectively securing the impact member to the posts, each connector comprising 10 a bowed leaf spring having laterally spaced ends rigidly secured to portions of the post angularly disposed with respect to the impact member, said spring being attached intermediate its ends to the impact member and having portions bowed in 15 opposite directions on opposite sides of the point of attachment of the spring to the impact member.
17. A road guard comprising a series of spaced posts, a flexible impact member extending along 20 said posts in spaced relation thereto, and means for connecting the impact member to each post including a bowed leaf spring of substantially a U-shape, each leg of the U being provided with a reverse bend and having its free end secured to 25 the post.
18. A road guard comprising a series of spaced posts, a flexible impact member extending along said posts, means for connecting the impact member to each post including a bowed leaf spring 30 having a reentrant bend in its rear face, each post having a portion extending into said reentrant bend of the associated spring for attachment thereto and said bend forming laterally spaced faces cooperable with the post.
- 35 19. A road guard comprising a series of spaced posts, a flexible impact member extending along said posts, means for connecting the impact member to each post including a resilient support in the form of a closed loop, said loop having a re- 40 entrant bend in its rear face for receiving a portion of the associated post, said bend providing the support with laterally spaced faces respectively cooperable with said portion of the post.
20. A road guard comprising a series of spaced 45 posts, a support secured to each post and having a reentrant front face, each support having an impact member of sheet metal overlapping its reentrant front face, and means for maintaining the impact member in engagement with portions 50 of the support adjacent opposite sides of said reentrant front face.
21. A device for connecting a sheet metal impact member of a road guard to a support, comprising a bowed leaf spring adapted to be secured 55 to the support and having a reentrant front face adapted to extend transversely of the direction of length of the impact member, and means adapted to draw the impact member into said re-entrant front face.
22. A road guard comprising a series of spaced posts, a flexible sheet metal impact member carried by said posts, a spring device attached to one of said posts and having a reentrant front face interposed between said impact member and 5 said posts, and means for securing a portion of the impact member in crimped relation with the reentrant front face of the spring device.
23. A road guard as described in claim 20, in which the reentrant front face of each support is 10 in spaced relation with the post to which the support is attached.
24. A device as described in claim 21, in which the reentrant front face of the bowed leaf spring is adapted to be disposed in spaced relation to the 15 support.
25. A road guard device as described in claim 22, in which the reentrant front face of the spring device is in spaced relation to the post to which 20 said device is attached.
26. A road guard comprising a series of spaced posts, a flexible impact member extending along said posts, resilient connectors secured to the posts for connecting the impact member thereto, each of said connectors having laterally spaced 25 portions offset from the associated post for cooperating with the impact member and the latter being deflected inwardly toward the posts between the laterally spaced portions of each of said connectors, and means cooperating with the inwardly 30 deflected portions of the impact member for securing the impact member to the connectors independently of said posts.
27. A road guard comprising a series of spaced 35 posts, a flexible impact member extending along said posts, and means for connecting the impact member in spaced relation to each post including a resilient support of loop form, said loop having laterally spaced portions disposed in spaced relation to the associated post for cooperating with the impact member and the latter having a deflected portion extending inwardly toward said post between the laterally spaced portions of the loop.
28. A road guard comprising a series of spaced 45 posts, a flexible impact member extending along said posts, resilient connectors secured to the posts for connecting the impact member thereto, and means connecting the impact member to said connectors independently of said posts, each of said 50 connectors having oppositely bowed portions extending on opposite sides of the means connecting it to the impact member and being provided with laterally spaced portions offset from the associated post for cooperating with the impact member, said impact member being deflected inwardly toward said posts between the laterally 55 spaced portions of each of said connectors.

EUGENE V. CAMP.
